CLAIM

The ornamental design for a mold for food, as shown and described.

DESCRIPTION

FIG. 1 is a top plan view of a mold for food showing my new design;

FIG. 2 is a top, front perspective view thereof;

FIG. 3 is a bottom plan view thereof; and,

FIG. 4 is a bottom perspective view thereof.

The broken line boundaries and dotted pattern areas within in FIGS. 3 and 4 represent portions of the mold for food that forms no part of the claimed design.

1 Claim, 4 Drawing Sheets
